UNITED STATES PATENT OFFICE

1,987,548

HEATER

Arthur Brooks, Galt, Ontario, Canada

Application June 17, 1932, Serial No. 617,897

3 Claims. (Cl. 126—75)

My invention relates to heaters, and particularly to improvements in solid fuel burning and gas burning heaters.

Important objects of the invention are to provide down draft means for intensifying the combustion in the heater, and surrounding conduits for conveying heated gases and products of combustion around the outside of the fire-box so as to increase the heat radiation value of the fuel consumed, together with means for withdrawing such gases and products of combustion from the fire pot in a manner to increase the combustion therein.

Other objects and advantages of my invention will be apparent from a reading of the following description in connection with the drawings, wherein for purposes of illustration I have shown a preferred embodiment of the invention.

In the drawings:

Figure 1 is a general transverse vertical sectional view through the embodiment from front to back.

Figure 2 is a transverse vertical sectional view through the embodiment taken approximately at right angles to Figure 1.

Figure 3 is a horizontal sectional view through the embodiment.

Figure 4 is a top plan view of Figure 1.

Figure 5 is a vertical transverse sectional view through the rear portion of the upper part of the heater.

Figure 6 is an elevational enlarged detail of the slide damper.

Figure 7 is a perspective view of a portion of the inner annulus of the fuel feed.

Referring in detail to the drawings, wherein like numerals refer to like parts throughout the same, the numeral 5 generally designates the casing of the device which may be square or round or any other desirable shape in a vertically elongated form. This may be constructed preferably of steel, or it may be of cast iron if desired, or of any other suitable material. The casing 5 may or may not be lined for the greater portion of its height with fire brick 6 or other suitable heat resisting material. The lower end of the fire brick 6 is spaced considerably above the floor 7 of the casing 5 which is preferably formed integral with the casing 5. In the solid fuel type, a conventional grate generally designated 8 may be horizontally supported within and across the casing at the lower end of the fire brick 6. As seen in Figure 2 the bars of this grate as indicated at 9 are preferably of triangular formation, the grate being of a type rockable

in a well known manner. In the front wall 10 of the stove below the grate 8 there is provided the ash pit opening 11 and the movable ash pit door 12. Opposite the ash pit opening 11 and in the back wall of the ash-pit is provided a slide damper generally designated 13 which is in the form of guide flanges 14, 15 carrying slidably therein the slide 16 provided with openings 17, 18 registrable with openings 19, 20 formed in the rear wall of the stove and with openings 19 formed in two adjacent conduits 31 for enabling the creation of check drafts.

The front casing wall 10 is provided in its upper part with a fire door opening 19a which is formed through the wall and through the fire brick 6 and is provided with a movable door 20a. The upper end of the casing 5 is provided with an exteriorly telescoping cover or if desired integrally formed with a diverging annular member 21a which forms a support for the top of the heater generally designated 21. At the rear of the casing 5 the upper end of the back wall is upwardly extended as indicated at 22' above the annular member 21a to engage the underside of the top wall 23 of the heater top 21 for supporting the same and act as a partition.

The top 21 comprises the top plate 23 with the outwardly flaring annular flange 24 depending therefrom and of a size to overhang the annular member 21a when seated thereon. The flange 24 is either attached or not to the annular member 21a as desired. The top plate 23 is provided with a square or round opening 25 which has an inwardly projecting depressed ledge 26, and from this downwardly and convergently extends the frusto-conical annulus 27 which depends into the fire pot of the stove to a point below the upper end of the fire brick 6 as seen in the drawings. A closure plate 29 may be utilized as a cover for the opening 25, and it is formed and shaped and of a proper size to rest upon the ledge 26 as seen in Figures 1 and 2 below the top plate 23.

The opening 25 with its ledge 26 and its depending frusto-conical annulus 27 forms the automatic fuel feeder, and this has telescoped into it the inner frusto-conical annulus 28 which is supported by means of circumferential lugs formed on its upper end and projecting laterally therefrom. The lugs engage the interior of the annulus 27 and support the annulus 28 within the annulus 27 in spaced relation therewith as can be seen in Figures 1 and 2. The spaced relation of the annuli 27 and 28 provides between them an annular chamber which when the heater is in operation acts to convey gases

which rise from the charge in the inner annulus 28 through the space between the annuli 27, 28 and into the burning fuel on the grate, which gases are largely composed of products of partial combustion of the fuel charge in the inner annulus 28, whereby the intensity of the combustion in the combustion chamber or fire-pot of the stove is favorably influenced, and economy in fuel secured.

10 Surrounding the back and two sides of the casing 5 is a series of spaced vertical tubular conduits 31. These have their lower ends communicated with a chamber 32 which is coextensive with the bottom 7 of the casing and 15 projects therebeyond at all sides. The front end of the chamber 32 is provided with a removable closure 33 for cleaning purposes. The upper ends of the conduits 31 at the back of the casing are communicated with the chamber 35 which ex- 20 tends on the back of the stove and therebeyond at the upper end thereof and which is constituted by the annulus 21a, the top generally designated 21, and the partition 22'. The partition 22' at the rear of the upper part of the casing 25 is provided with a longitudinal opening 36 which communicates the chamber 35 with the interior of the casing. The conduits 31 at the opposite sides of the casing extend between and connect the overhanging sides of the top of the casing 30 and of the chamber 32 so that gases and other products of combustion may pass outwardly from the interior of the casing and downwardly through the side conduits 31 into the lower chamber 32 and upwardly through the back con- 35 ducts 31 to the chimney opening at the back of the top of the casing. This action of the gases and products of combustion heats the conduits 31 which, in turn, radiate the heat to efficiently heat a room or the like. The damper 40 opening 36 in the partition 22' is provided for creating a direct draft for the stove as when starting a fire therein. As seen, the products of combustion finally escape through the chimney collar 39. In this way a relatively small amount 45 of fuel expenditure secures a large radiation of heat. If desired arrangement may be made whereby to circulate the gases and products of combustion upwardly at one side of the stove and downwardly at the other instead of in the 50 manner described.

For controlling the passage of gases and products of combustion in the manner described the opening 36 in the partition 22' is provided with a hingedly mounted damper 37 which is operable 55 at the rear of the top through the agency of a rod 38 projecting from the structure.

As shown, the conduits 31 are considerably spaced apart, but if desired, this spacing may be reduced and the size and contour of the 60 conduits altered according to the results desired and the size and shape of the heater upon which they are applied.

Though I have shown and described herein a preferred embodiment of the invention, it is to 65 be definitely understood that I do not desire to limit the application of the invention thereto, and any change or changes may be made in material and structure of parts within the spirit of the invention, and the scope of the subjoined 70 claims. It will be obvious that a gaseous fuel burner means could easily be substituted for the solid fuel burning means in the invention and the same advantages of heating efficiency obtained.

What is claimed is:

1. A heater comprising a closed casing having a grate above its lower end having an upper chamber and a lower closed chamber closing the upper and lower ends of the casing, said chambers being extended beyond the sides and beyond the back of the casing, a multiplicity of side vertical tubes extending between and communicating with laterally extending portions of said upper and lower chambers on opposite sides of the casing, a second multiplicity of vertical tubes extending between and communicating with a rearwardly extending portion of said upper and lower chambers at the back of the casing, a flue connection on the extended portion at the back 10 of the upper chamber above the upper ends of the back tubes, a partition within and across a rear portion of said upper chamber and defining with the back wall of the casing a third chamber with which said flue connection and the upper 15 ends of the back tubes communicate, a part of the back wall of said casing above and adjacent the lower end thereof being provided with opening means communicating with the air space immediately below said grate and with the lower 20 part of some of said back tubes, and means for opening and closing said opening means, and air inlet means in the front wall of said lower 25 closed chamber permitting air to be drawn into said lower closed chamber and to be drawn upwardly through the charge and then passed downwardly through the side tubes and upwardly through the back tubes and through said third chamber and to said flue connection.

2. In a heater, a generally rectangular casing 35 having a grate above its lower end and an air inlet below said grate, a housing closing the top of said casing and having portions overhanging the opposite sides and the back of said casing, a partition extending across the back and between the sides of said housing and defining with the back wall of said housing a chamber, a closed second chamber closing the bottom of said casing below said air inlet, a plurality of tubes at each side of the casing whose opposite 40 ends communicate with the overhanging side portions of said housing and with said second chamber, a third plurality of tubes having their opposite ends communicating with the first mentioned chamber and with a back part of said second chamber whereby air entering by said air 45 inlet is drawn upwardly in said casing then flows downwardly through the side tubes to said second chamber, then upwardly through the back tubes to the first mentioned chamber, said partition being substantially vertically aligned with the back wall of the casing, and flue means opening through the top of said first mentioned chamber, the back wall of said casing having a check-draft opening in its lower part communicating 50 with the air space immediately below said grate and the lower part of some of said back tubes, and means for opening and closing said check-draft opening.

3. In a heater, a generally rectangular casing 65 having a grate above its lower end and an air inlet below said grate, a housing closing the top of said casing and having portions overhanging the opposite sides and the back of said casing, a partition extending across the back and between the sides of said housing and defining with the back wall of said housing a chamber, a closed second chamber closing the bottom of said casing below said air inlet, a plurality of tubes at each side of the casing whose opposite 70 ends communicate with the overhanging side portions of said housing and with said second chamber, a third plurality of tubes having their opposite 75 ends communicating with the first mentioned chamber and with a back part of said second chamber whereby air entering by said air inlet is drawn upwardly in said casing then flows downwardly through the side tubes to said second chamber, then upwardly through the back tubes to the first mentioned chamber, the back wall of said casing having a check-draft opening in its lower part communicating with the air space immediately below said grate and the lower part of some of said back tubes, and means for opening and closing said check-draft opening.

ends communicate with the overhanging side portions of said housing and with said second chamber, a third plurality of tubes having their opposite ends communicating with the first mentioned chamber and with a back part of said second chamber, said partition being substantially vertically aligned with the back wall of the casing, and flue means opening through the top of said first mentioned chamber, the back 5 wall of said casing having a checkdraft opening

in its lower part communicating with the air space immediately below said grate and the lower part of some of said back tubes, and means for opening and closing said checkdraft opening, said partition having a restricted opening provided with a movable damper permitting rise of air and products of combustion from the interior of the casing to said flue connection without passing first through said tubes. 5

ARTHUR BROOKS. 10
